United States Patent Office.

CORNELIUS ST. JOHN AND CHARLES E. MARSTON, OF CHARLESTOWN,
MASSACHUSETTS.

Letters Patent No. 97,825, dated December 14, 1869.

IMPROVED MODE OF FORMING "BURNER-CONES" OF LAMPS.

The Schedule referred to in these Letters Patent and making part of the same.

To all whom it may concern:

Be it known that we, CORNELIUS ST. JOHN and CHARLES E. MARSTON, both of Charlestown, in the county of Middlesex, and State of Massachusetts, have invented an Improvement in Lamp-Burners; and we do hereby declare that the following, taken in connection with the drawings, which accompany and form part of this specification, is a description of our invention, sufficient to enable those skilled in the art to practise it.

This invention has particular reference to the construction of burner-cones, or flame-shields for kerosene and other lamps; and

The invention consists in forming such a shield in the shape of a hollow bust or thin shell, made to represent a head or other figure, such shell being preferably formed in one piece by chemically depositing the metal upon a suitable frame or core.

The drawing represents a shield, called in the trade a "cone" or "burner-cone," embodying our invention.

a denotes an ordinary wick-tube, rising from the screw-cap *b*.

c denotes the shield, which, as shown in the drawings, is made with a surface representing a figure-head, instead of being formed with a regular curved contour, as are all common burner-cones.

The shield is hollow, and has a flame-orifice, *d*, opening out of its top, and the shell may be formed in parts, in separate dies, the parts being then joined together at their edges to form the whole shell.

We prefer, however, to make the shell in one piece by depositing the metal (preferably copper) by means of a battery upon a paper or other mould or core, which can be removed after the shell is formed.

The outer surface may be plated with silver, or other bright metal, to give the surface a desirable lustre.

e denotes the flange, for supporting the glass chimney, and *f*, the fingers, which hold the chimney in place; and to slip the head upon the flange, the shell may be formed with a flange, *g*, to slip under projections, *h*, on the flange *e*.

It will be obvious that a burner-cone or shield thus made adds to the ornamental appearance of a lamp, and imparts an increased marketable value to such cones or shields over the common burner-cones.

The shell may be made of other ornamental figure or representation, and may be used as a flame tube or burner without a wick tube, though we intend it more particularly as an improvement upon the common kerosene-burners.

We claim, as a new article of manufacture, a flame-shield or burner, made of a thin shell of metal, formed into shape by electro-deposit of the metal upon a suitable pattern.

CORNELIUS ST. JOHN.
CHARLES E. MARSTON.
